Attorney

UNITED STATES PATENT OFFICE

152,756

DESIGN FOR A BILLFOLD OR SIMILAR ARTICLE

Harry I. Thomas, Hagerstown, Md., assignor to
The Hagerstown Leather Co., Hagerstown, Md., a corporation of Maryland

Application May 2, 1946, Serial No. 129,228

Term of patent 7 years

(Cl. D87—3)

To all whom it may concern:

Be it known that I, Harry I. Thomas, a citizen of the United States, residing at Hagerstown, in the county of Washington and State of Maryland, have invented a new, original, and ornamental Design, for a Billfold or Similar Article, of which the following is a specification, reference being had to the accompanying drawing, forming part thereof.

Figure 1 is a view in plan of a billfold embodying my new design, the opposite face being plain; and

I claim:

The ornamental design for a billfold or similar article, substantially as shown and described.

HARRY I. THOMAS.
